(57) **CLAIM**

The ornamental design of a table leg, as shown and described.

DESCRIPTION

FIG. 1 is an isometric view of a table leg incorporating my new design, in which phantom lines indicate features forming no part of the claimed design and indeterminate length;

FIG. 2 is a left side elevation view thereof;

FIG. 3 is a front elevation view thereof;

FIG. 4 is a right side elevation view thereof;

FIG. 5 is a rear elevation view thereof;

FIG. 6 is a top plan view thereof;

FIG. 7 is a bottom plan view thereof;

FIG. 8 is an isometric view showing another embodiment of a table leg incorporating my new design;

FIG. 9 is a left side elevation view thereof;

FIG. 10 is a front elevation view thereof;

FIG. 11 is a right side elevation view thereof;

FIG. 12 is a rear elevation view thereof;

FIG. 13 is a top plan view thereof; and,

FIG. 14 is a bottom plan view thereof.
